CAN OR THE LIKE

Arthur P. Zundel, Chicago, Ill., assignor to National
Can Corporation, Chicago, Ill.

Filed Nov. 23, 1971, Ser. No. 201,607

Term of patent 14 years

Int. Cl. D9—03

U.S. Cl. D9—218

FIG. 1

FIG. 2

FIG. 4

FIG. 3

FIG. 1 is a perspective view of a can showing my new design;

FIG. 2 is an enlarged scale perspective view of a portion of the can shown in FIG. 1;

FIG. 3 is a side elevational view of the device shown in FIG. 2; and

FIG. 4 is a top view thereof.

I claim:

The ornamental design for a can or the like, substantially as shown.
